UNITED STATES PATENT OFFICE.

ALFRED B. LORD, OF CAMBRIDGE, MASSACHUSETTS, ASSIGNOR OF ONE-THIRD TO F. J. PICKMAN AND ONE-THIRD TO WILLIAM A. SOUTHAM, BOTH OF CLEVELAND, OHIO.

WRENCH.

1,276,236.

Specification of Letters Patent. Patented Aug. 20, 1918.

Application filed December 17, 1917. Serial No. 207,570.

To all whom it may concern:

Be it known that I, ALFRED B. LORD, a citizen of the United States, residing at Cambridge, in the county of Middlesex and 5 State of Massachusetts, have invented certain new and useful Improvements in Wrenches, of which the following is a specification.

This invention relates to wrenches, and 10 has for its object to provide a new and improved construction with respect particularly to the shank connections between two members which respectively carry inner and outer jaws, the construction being such that 15 when pressure is applied to the shank handle the jaws will move toward each other, and the shank members will engage and interlock with each other, forming a strong and rigid handle without the liability of breakage 20 found in other wrenches of a similar type.

A further object of the invention is to provide a wrench composed of separate members which can be properly tempered, said members being fastened together to produce the complete wrench. 25

Other objects and advantages will appear from the following description.

In the accompanying drawings—

Figure 1 is a side view of the wrench.

30 Fig. 2 is a similar view showing the wrench applied to a pipe.

Fig. 3 is a side view of the wrench with the members separated.

Referring specifically to the drawings, 35 indicates the outer jaw the angular face of which is provided with teeth 3^a. This jaw is integral with a shank section 3^b, and the inner face or edge of this shank section is provided with a plurality of shoulders 5, 5^a, 40 5^b and 5^c. The shoulders 5 and 5^a are presented outwardly or toward the jaw. The shoulders 5^b and 5^c are oppositely presented and are located near the rear end of the shank and form in effect a dovetail cross 45 groove or mortise which serves for the reception of a dovetail tenon or projection 4^b on the other member.

This other member comprises an inner jaw 4, the face of which is angular and smooth, 50 and located at a proper angle with respect to the outer jaw 3 to grip a pipe or other article placed between the jaws. The jaw 4

is integral with a shank section 4^a, and the inner edge of this shank section has downwardly presented shoulders 4^c and 4^d which 55 correspond with the shoulders 5 and 5^a on the other shank section. The outlines of the two shank sections match to produce a complete handle.

When the sections are assembled the dovetail tenon 4^b is fitted in the recess between the shoulders 5^b and 5^c and the sections are fastened together by a riveted pin 6 passed through suitable holes in the sections. 60

In use, when the wrench is applied to a pipe or the like, as shown in Fig. 2, and pressure is applied to the handle, the shank of the inner jaw yields inwardly and the shoulders 4^c and 4^d abut against or interlock with the shoulders 5 and 5^a, thereby locking the 70 two shank members together in a direction to resist the stress and strain on the handle and forming in effect a solid handle of great strength and rigidity. When the pressure is released the shank of the inner jaw recedes 75 to original position.

This wrench has decided advantages with respect to manufacture, because the two members can be separately and properly tempered and are much easier to manufacture. The jaw faces are disposed at such an angle that when in action the upper and lower jaw come in closer proximity to each other thus insuring a more effective grip on an article between the same, and the dovetail connection at the rear end relieves any shearing strain on the connecting rivet between the members. Furthermore, this wrench does not depend on any pivotal point of action, the desired result is obtained by 80 the yielding spring action of the inner jaw member.

I claim:

1. A wrench comprising outer and inner shank handle members provided with outer and inner jaws respectively, said members being fastened together at their rear ends, the outer member having a forwardly presented shoulder on its inner edge, and the inner member having a co-operating rearwardly presented shoulder on its edge adjacent the outer member, said members being adapted to spring together in use to engage 95 said shoulders with each other. 100

2. A wrench comprising inner and outer shank handle members provided with inner and outer jaws respectively at their front ends and adapted to spring toward each other under pressure, said members having a dovetail connection between each other at their rear ends.

In testimony whereof, I do affix my signature in presence of two witnesses.

ALFRED B. LORD.

Witnesses:

WILLIAM A. SOUTHAM,
F. J. PICKMAN.
